UNITED STATES PATENT OFFICE.

CHARLES A. ALDEN, OF STEELTON, PENNSYLVANIA, ASSIGNOR TO THE PENNSYLVANIA STEEL COMPANY, OF PHILADELPHIA, PENNSYLVANIA, A CORPORATION OF PENNSYLVANIA.

RAILWAY-FROG.

No. 840,547.

Specification of Letters Patent.

Patented Jan. 8, 1907.

Application filed February 3, 1906. Serial No. 299,276.

To all whom it may concern:

Be it known that I, CHARLES A. ALDEN, a citizen of the United States, residing at Steelton, in the county of Dauphin and State of Pennsylvania, have invented certain new and useful Improvements in Railway-Frogs, of which the following is a full, clear, and exact description, reference being had to the accompanying drawings, of which—

10 Figure 1 is a plan view of a railway frog or crossing in which my invention is embodied, the wear-plate being shown in place as in use; but for better illustration the same is shown before the spelter metal has been poured in. Fig. 2 is a vertical section on line *xx*, Fig. 1. Fig. 3 is a section on line *yy*, Fig. 2. Fig. 4 is a section on line *zz*, Fig. 1, the spelter metal being shown in this view.

This invention relates to improvements in 20 railway crossings, frogs, or the like, in which the hard-metal wear-plate is intended to be renewable, and is therefore made separate from and removably secured to the supporting-base.

25 The object of the invention is to provide a frog or the like in which the wear-plate is secured to the base by such means that while the wear-plate may be readily secured to and detached from said base without disturbing 30 the paving of the street, it shall be firmly secured thereto without liability to fracture of any of the parts or displacement of the wear-plate when in use.

The precise character of the invention will 35 clearly appear from the following description, in connection with the drawings, which illustrate a railway-frog in which the invention is embodied.

1 is the base, and 2 the hard-metal wear-plate. These two parts are substantially 40 similar to the corresponding parts of well-known frogs or crossings of this class, except in certain details required by this invention. The top of the base 1 is formed with a depression 3, preferably of the form in cross-section shown in Fig. 4—that is, with a midway longitudinally-extending groove 4 and the bottom of the wear-plate, which is of a shape to fit said depression, being provided 45 with a downwardly-extending rib 5, entered into said groove 4, as shown. This rib, in addition to preventing displacement of the wear-plate, serves to prevent any vertical

buckling of the plate due to the tendency to stretch on its upper surface under the strains of heavy traffic thereover. 55

The base is provided with oblique recesses 6, four in this instance, occupying the corners of a rectangle, as seen in Fig. 1. These recesses are open at their upper ends at the top 60 of the base 1, and their inner portions open into the sides of the depression 3, as seen in Figs. 1 and 2, so that access to said recesses may be had from the depression 3 when the wear-plate is not in place in said depression, 65 for a purpose hereinafter set forth. The wear-plate 2 is provided with laterally-extending inclined lugs 7, that extend into the recesses 6 substantially at right angles to the inclination thereof, which in this instance is 70 an angle of forty-five degrees to the level of the top of the base. Each of these lugs 7 is provided with a hole 8 therethrough, through which passes a bolt 9.

The recesses 6, somewhat below lugs 7, are 75 each provided with an upper wall, dividing said recesses into upper and lower portions, marked 6^a and 6^b, respectively. In this instance said wall is formed from the crown 10 of an inverted-U-shaped piece 11 of 80 tough metal that is capable of withstanding severe tensile strain, the lower outwardly-turned ends 12 of the legs of which tough-metal piece are firmly embedded deep in the body of the casting, for a purpose herein-after explained. The lower ends, respectively, of bolts 9 are screwed into nuts 13 within the lower portion 6^b of recesses 6—that is, below the wall 10—and thereby said nuts are tightly drawn upwardly against the 85 under surface of said wall, the bolt-heads 9^a firmly holding the lugs 7 in place within the recesses 6, and thereby the wear-plate is secured rigidly in place to the base. The heads of bolts 9 are usually provided with a 90 squared socket 9^b for the insertion of the key through the top of recesses 6 to unscrew or tighten the bolt 9 and so release or secure the wear-plate in place, as described. 95

In assembling the parts the proceeding is 100 quite simple, being as follows: Prior to inserting the wear-plate in the depression 3 the nuts 13 are from the depression 3 placed in the lower portion 6^b of the recesses 6 below the walls 10. The wear-plate is then seated 105 in the depression 3, with the lugs 7 thereof

extending into the portion 6^a of the recesses 6 above the walls 10. The bolts 9 are then passed through holes 8 in the lugs 7, thence through registering holes 14, through walls 10, and their lower ends screwed into the nuts 13, thereby drawing said nuts upwardly against the under surfaces of said walls and so securing the wear-plate firmly in place to the base.

10. The purpose of making the wall 10 as the crown of the inverted-U-shaped piece 11 of tough metal instead of having it a part of the casting of the base 1 is so that said wall, upon which a heavy strain comes, shall be of strong material, and also by embedding the lower ends of the legs of the piece 11 deep down in the casting of the base the strain on said piece is transferred to the base at points where the casting is of great thickness and strength. The pieces 11, of tough metal, would usually in practice be cast into place in the base 1 in the process of molding said base.

15. The wear-plate is usually made slightly smaller than the depression 3, so as to leave a space surrounding said wear-plate when in place for the insertion of spelter metal, such spelter metal being shown at 15, Fig. 4, and in practice would also fill the portion of recesses 6 above the heads of bolts 9. The purpose of the spelter metal, as is well-known in this class of frogs or crossings, is to take up any irregularities in either the under side of the wear-plate or the upper surface of the depression 3 of the base-casting 1, so that the street-surface of the wear-plate may be always at the proper level; also, the spelter metal serves as a temporary filling for the portion of said recesses 6 above the bolt-heads 9^a, which may be chipped out when it is desired to unscrew said bolts to remove the wear-plate. I further remark that in addition to being readily renewable without disturbing the paving of the street the wear-plate of my invention is not liable to work loose, and owing to the axes of the securing-bolts 9 being at an angle of substantially forty-five degrees to the street-level they are not liable to fracture from any turning strains 20 to which the wear-plate may be subjected.

Having thus described my invention, I claim as new and desire to secure by Letters Patent—

1. The combination of the base having the

depression therein, and the recesses open at 55 their upper ends and whose inner sides communicate with said depression, the walls in said base dividing said recesses into upper and lower portions, the wear-plate seated in said depression, and having the lugs extending 60 into said upper portions of said recesses respectively, together with the nuts in the lower portions respectively, of said recesses, and the bolts passing through said lugs and said walls, and engaging said nuts, substantially as set forth.

2. The combination of the base, having the depression therein, and the recesses open at 70 their upper ends and whose inner sides communicate with said depression, said recesses extending into said base at substantially an angle of forty-five degrees to the level thereof, the walls in said base dividing said recesses into upper and lower portions, the wear-plate seated in said depression and 75 having the lugs extending therefrom at substantially an angle of forty-five degrees into the upper portions of said recesses, respectively, together with the nuts in the lower portions respectively of said recesses, and the 80 bolts passing through said lugs at right angles thereto, and through said walls, and engaging said nuts, substantially as set forth.

3. The combination of the base having the depression therein, and the recesses open at 85 their upper ends and whose inner sides communicate with said depression, the hard-metal pieces within said recesses and having upper portions constituting transverse walls across said recesses, dividing the same into 90 upper and lower portions, said hard-metal pieces having portions extending downwardly from said wall portions and embedded deep in the casting of the base, the wear-plate seated in said depression, and having 95 the lugs extending therefrom into said upper portions of said recesses respectively, together with the nuts in the lower portions respectively of said recesses, and the bolts passing through said lugs and said wall portions 100 of said hard-metal pieces, and engaging said nuts, substantially as set forth.

In testimony whereof I have hereunto affixed my signature.

CHARLES A. ALDEN.
